(57) **CLAIM**

The ornamental design for an ohmmeter, as shown and described.

DESCRIPTION

FIG. 1 is a front elevation view of the ohmmeter showing the new design.

FIG. 2 is a right side, elevation view of the ohmmeter shown in FIG. 1.

FIG. 3 is a bottom, plan view of the ohmmeter shown in FIG. 1.

FIG. 4 is a top, plan view of the ohmmeter shown in FIG. 1.

FIG. 5 is a left side, elevation view of the ohmmeter shown in FIG. 1.

FIG. 6 is a rear, elevation view of the ohmmeter shown in FIG. 1; and,

FIG. 7 is a perspective view of the ohmmeter shown in FIG. 1.

Broken lines shown in the drawings are for the purpose of illustrating environmental structure or to define boundaries and form no part of the claimed design.
